US0D1012129S

(12) **United States Design Patent** (10) **Patent No.:** **US D1,012,129 S**
(45) **Date of Patent:** **** Jan. 23, 2024**

(54) **PORTABLE AIR COMPRESSOR**

(71) Applicant: **The Noco Company**, Glenwillow, OH (US)
(72) Inventors: **Derek Michael Underhill**, Chandler, AZ (US); **Matthew Michael Bosway**, Queen Creek, AZ (US); **Jonathan Lewis Nook**, Gates Mills, OH (US); **William Knight Nook**, Shaker Heights, OH (US); **James Richard Stanfield**, Glendale, AZ (US)

(73) Assignee: **The Noco Company**, Glenwillow, OH (US)

(**) Term: **15 Years**

(21) Appl. No.: **29/863,121**

(22) Filed: **Dec. 15, 2022**

(57) **CLAIM**

The ornamental design for a portable air compressor, as shown and described.

DESCRIPTION

FIG. 1 is a perspective view of a new design for a portable air compressor;

FIG. 2 is another perspective view thereof;

FIG. 3 is a top view thereof;

FIG. 4 is a bottom view thereof;

FIG. 5 is a left side view thereof;

FIG. 6 is a right side view thereof;

FIG. 7 is a front view thereof;

FIG. 8 is a rear view thereof;

FIG. 9 is a further perspective view thereof with hinged port access doors in an open position;

FIG. 10 is the perspective view of FIG. 9 with the hinged port access doors in a closed position; and,

FIG. 11 is an even further perspective view with a pressure hose in an extended configuration.

The broken lines in the drawings depict environmental structure of the portable air compressor that form no part of the claimed design.
